UNITED STATES PATENT OFFICE

HARRISON J. COWAN, OF DOUGLASTON, NEW YORK, ASSIGNOR TO KINATOME PATENTS CORPORATION, OF NEW YORK, N. Y., A CORPORATION OF NEW YORK

DESIGN FOR A COMBINED CABINET AND SCREEN FOR A MOTION PICTURE PROJECTOR

Application filed July 21, 1932. Serial No. 44,400. Term of patent 7 years.

To all whom it may concern:

Be it known that I, HARRISON J. COWAN, a citizen of the United States, residing at 7 Beverley Road, Douglaston, in the county of Queens and State of New York, have invented a new, original, and ornamental Design for a Combined Cabinet and Screen for a Motion Picture Projector, of which the following is a specification, reference being had to the accompanying drawing, forming part thereof.

Figure 1 is a front elevational view of the combined cabinet and screen, the screen being positioned adjacent the top of the cabinet and the back of the combined cabinet and screen being plain and unornamented.

Figure 2 is a side elevational view of the structure shown in Figure 1, the opposite side of the structure having the same appearance as the side shown.

I claim:

The ornamental design for a combined cabinet and screen for a motion picture projector, substantially as shown and described.

Signed at New York, in the county of New York and State of New York, this fourteenth day of July, 1932.

HARRISON J. COWAN.
